FIG. 7-

UNITED STATES PATENT OFFICE.

GEORGE C. JENSEN, OF OAKLAND, CALIFORNIA.

GEAR-SHIFT-LEVER LOCK MECHANISM.

1,262,349.

Specification of Letters Patent. Patented Apr. 9, 1918.

Application filed February 19, 1918. Serial No. 218,034.

To all whom it may concern:

Be it known that I, GEORGE C. JENSEN, a citizen of the United States, residing at Oakland, in the county of Alameda and State of California, have invented certain new and useful Improvements in Gear-Shift-Lever Lock Mechanism, of which the following is a specification.

The present invention relates to a lock for shift devices particularly levers of the type wherein the lever member is fulcrumed for universal movement within a supporting member and wherein the lever or support is provided with one or more pins co-operating with the other member to control the swinging movement of the lever, the lock capable of positioning to overlie the pins in contact therewith precluding the movement of the pin in its slot, thereby locking the lever from operative movement.

With the above mentioned and other objects in view, the invention consists in the novel construction and combination of parts hereinafter described, illustrated in the accompanying drawings and pointed out in the claims hereto appended, it being understood that various changes in the form, proportion, size and minor details of construction within the scope of the claims may be resorted to without departing from the spirit or sacrificing any of the advantages of the invention.

To more fully comprehend the invention reference should be had to the accompanying sheets of drawings wherein:

Figure 1 is a vertical sectional view of the preferred embodiment of my invention, taken on line 1—1 of Fig. 2.

Fig. 2 is a top plan view with the upper portion of the lever in section.

Fig. 3 is a sectional view taken on line 3—3 of Fig. 2.

Fig. 4 is a sectional view taken on line 4—4, of Fig. 3.

Fig. 5 is a vertical sectional view of a modified form of construction.

Fig. 6 is a top plan view of the modified form of construction illustrated in Fig. 5.

Fig. 7 is a sectional view taken on line 7—7, Fig. 5.

Referring more particularly to the several views of the drawings, wherein like characters of reference designate corresponding parts, 1 indicates a tubular sup-

porting member, at the upper end of which 55 is provided a spherical seat 2 for receiving the spherical portion 3 of a lever 4 depending thereinto, said support providing a universal fulcrum for the lever.

The lever is provided with the laterally 60 extended oppositely disposed pins 5 which extend into vertical cutouts or slots 6 in the wall of said spherical seat 2, said pins permitting movement of the lever in planes at right angles to each other, but precluding 65 axial rotation of the same. The upper surface of each pin 5 is flattened or faced as at 7 and said flattened portions or faces lie flush with the upper surface of the supporting member 1.

Positioned over the upper portion of the lever and moved downwardly thereon to rest at its lower edge on the upper surface of the supporting member 1 is a retaining ring or collar 8 to the lower end of which is secured in any suitable manner, as by threading, a retaining ring member 9 between which and the laterally extending oppositely disposed ears 10 on the upper surface of said member 8 is retained the flanged portion 11 of an annular retaining member 12, which is detachably secured in position to the upper surface of the supporting member 1 by headed screws or other attaching members 13. An annular flange 14 is provided 85 on the member 12 and the same extends downwardly for a short distance around the upper end of the supporting member 1.

An operating handle 15 extends from one of the ears 10 and the same permits of the 90 movement axially of the lever of the ring 9 and member 8, and on the positioning of said member 8, as in Fig. 2 of the drawings, said ears 10 overlie the heads of the screws 13 and prevent the detachment of said member 12 from the upper end of the supporting member 1 by the removal of the screws.

The retaining ring member 9 is formed on its periphery with the oppositely disposed lugs 15, which are adapted when the 100 member 8 is in the position as in Fig. 2 of the drawings, to overlie the pins 5 and contact with the upper surfaces 7 thereof, thus preventing movement of the lever within its socket and maintaining the same vertically 105 disposed therein. On the movement of the member 8 to uncover the upper ends of the screw members 13, said lugs 15 are removed

from over the pins 5, and the recesses 16 in the undersurface of said ring 9 are positioned over said pins, thereby admitting of universal swinging movement of the lever 5 within its socket. A coiled spring 17 normally maintains the member 8 in unlocked position, said spring being secured at one end to a pin 18 carried by the member 12, and its opposite end to a lug 19 carried by 10 the ring 9, said last mentioned lug 19 contacting with one of the screws 13 to limit the movement of the member 9 to locking position. A locking lug 20 is also carried by the periphery of the ring 9 and when the same is 15 in contact with one of the screws 13, as in Fig. 4 of the drawings, said lug is engaged by a spring-pressed locking bolt 21 longitudinally movable within a horizontal bore 22 formed within a boss 23 at one side of 20 the member 12. The locking bolt is adapted to be moved to unlocked or retracted position against the tension of the spring 24 by the operation of the eccentrically disposed finger 25 carried by the lower end of a rotatable locking barrel 26 preferably of the usual key controlled type, said finger extending into an elongated recess 27 in the upper portion of the locking bolt, 21.

It will be apparent that when it is desired to lock the lever from movement, the operator engages the handle 15 and moves the same axially of the lever in a clockwise direction against the tension of the spring 17, and when the lugs 15 overlie the upper 30 flat faces 7 of the pins 5, the lug 19 contacting with the shank of one of the screws 13 will arrest the movement of said member 8, at which time the locking bolt 21 will automatically engage the lug 20. This operation 35 positions the ears 10 over the heads of the screws 13 and prevents detachment of the member 11 from the supporting member 1.

When it is desired to unlock the lever to permit movement thereof, the operation of the barrel 26 will retract the locking bolt 21 and release the same from the lug 20, at which time the spring 17 will axially rotate the ring 9 and member 8 to position the recesses 16 to overlie the pins 5, at which time the lever is capable of universal swinging movement, and if desirable access may be had to the heads of the screws 13 to admit of the detachment of the member 12 from 50 the supporting member 1.

In the form illustrated in Figs. 5, 6 and 7, the supporting member 1 is formed with an upwardly disposed annular threaded flange 28 to which is secured, by threading, the ring 60 or collar 29, which surrounds the lever and bears at its lower end on the spherical portions 3 of said lever, maintaining the same seated in the socket 2. The supporting member 1 is further provided with a boss 30, in 65 which is mounted a locking plunger 31 out-

wardly pressed by a spring 32, the plunger extending beyond the threaded flange 28 and engaging in a recess 33 in said ring or collar 29. The inner surface of the ring or collar 29 is adapted when in its lowermost position 70 to lie substantially flush with the upper flat faces 7 of the pins 5 projecting laterally from the spherical portion 3 of the lever, and said undersurface is further provided with recesses 34 for overlying said pins 5 75 when the ring or member 29 is axially rotated to unlocked position and permit of universal movement of the lever within its socket. The engagement of the locking bolt 31 in the recess 33 is at such time as the member 29 is axially rotated to position the solid portion of the undersurface thereof to overlie the upper flat faces 7 of the pins 5, at which time the unthreading of the ring 29 from the support 1 is prevented, and the 80 movement of the lever within its socket is also precluded.

As in the other form of construction, the bolt 31 is retracted by the axial rotation of the locking barrel 26 having the usual eccentric portion 25 depending into an elongated recess 27 in said bolt.

It will be observed in the preferred embodiment of my invention, that on the retracting of the locking bolt 21 the ring 9 95 and member 8 are automatically rotated by the action of the spring 17 to unlock the lever to permit of universal movement thereof, while in the modified form of construction, both the locking operation and the unlocking operation are manually performed.

Having thus described my invention, what I claim as new and desire to protect by Letters Patent is:—

1. In combination with a tubular supporting member, a lever member removably supported thereby and fulcrumed therein for universal swinging movement, one of said members provided with a slot, the other of said members provided with a pin projecting within said slot and capable of movement therein on the operation of the lever, said coöperating pin and slot preventing axial rotation of the lever within the support, and lock controlled means carried by 115 said slotted member and capable of positioning to preclude movement of said pin within said slot and lock said lever from movement on its fulcrum.

2. In combination with a tubular supporting member, a lever member removably supported thereby and fulcrumed therein for universal swinging movement, one of said members provided with a slot, the other of said members provided with a pin projecting within said slot and capable of movement therein on the operation of the lever, said coöperating pin and slot preventing axial rotation of the lever within the support, and lock controlled means carried 125 by 130

- by said slotted member and capable of positioning to preclude movement of said pin within said slot and lock said lever from movement on its fulcrum or removal therefrom.
3. In combination with a tubular supporting member, a lever member supported thereby and fulcrumed therein for universal swinging movement, said supporting member provided with a slot, a coöperating pin extending laterally from said lever and into said slot, said pin and slot precluding axial rotation of the lever within said support, said pin movable within said slot on the movement of said lever, and a lock controlled member carried by the supporting member and capable of axial rotation relatively to the lever for positioning its surface to preclude movement of said pin within said slot and thus lock said lever from movement on its fulcrum.
4. In combination with a tubular supporting member provided with a spherical socket, a lever member provided with a spherical fulcrum portion removably seated within said spherical socket, said spherical socket provided at opposite sides with a vertical slot, a pair of pins extending laterally from said spherical fulcrum portion and projecting one into each of said slots and capable of movement therein on the operation of the lever, said pins each provided with a flat surface, and a lock controlled means movably supported by said tubular supporting member and capable of rotation thereon axially of the lever to position a portion of its surface to engage said flat pin faces to lock said lever from movement on its fulcrum.
5. In combination with a tubular supporting member provided with a spherical socket, a lever member provided with a spherical fulcrum portion removably seated within said spherical socket, said spherical socket provided at opposite sides with a vertical slot, a pair of pins extending laterally from said spherical fulcrum portion and projecting one into each of said slots and capable of movement therein on the operation of the lever, said pins each provided with a flat surface, a ring surrounding the lever above the spherical portion thereof and capable of axial movement relatively to the lever, said ring formed on its undersurface with recesses adapted to register with said pins to permit movement of the lever on its fulcrum, a retaining ring or plate secured to said ring for holding said axially rotatable ring in position thereon, and lock controlled means carried by said ring or plate for locking said axially rotatable ring from movement on the rotation of the same to position the recesses on the undersurface thereof out of register with said pins.
6. In combination with a tubular supporting member provided with a spherical
- socket, a lever member provided with a spherical fulcrum portion removably seated within said spherical socket, said spherical socket provided at opposite sides with a vertical slot, a pair of pins extending laterally from said spherical fulcrum portion and projecting one into each of said slots, said pins each provided with a flat surface, a ring surrounding the lever above the spherical portion thereof and capable of axial movement relatively to the lever, said ring formed on its undersurface with recesses adapted to register with said pins to permit movement of the lever on its fulcrum, a retaining ring or plate secured to said ring for holding said axially rotatable ring in position thereon, and lock controlled means carried by said ring or plate for locking said axially rotatable ring from movement on the rotation of the same to position the recesses on the undersurface thereof out of register with said pins.
7. In combination with a tubular supporting member provided with a spherical socket, a lever member provided with a spherical fulcrum portion removably seated within said spherical socket, said spherical socket provided at opposite sides with a vertical slot, a pair of pins extending laterally from said spherical fulcrum portion and projecting one into each of said slots and capable of movement therein on the operation of the lever, said pins each provided with a flat surface, a ring surrounding the lever above the spherical portion thereof and capable of axial movement relatively to the lever, said ring formed on its undersurface with recesses adapted to register with said pins to permit movement of the lever on its fulcrum, a retaining ring or plate secured to said ring for holding said axially rotatable ring in position thereon, and lock controlled means carried by said ring or plate for locking said axially rotatable ring from movement on the rotation of the same to position the recesses on the undersurface thereof out of register with said pins.
8. In combination with a tubular supporting member provided with a spherical socket, a lever member provided with a spherical fulcrum portion removably seated within said spherical socket for universal swinging movement therein, said spherical socket provided at opposite sides with a vertical slot, a pair of pins extending laterally from said spherical fulcrum portion and projecting one into each of said slots, said pins each provided with a flat upper face, and a lock controlled means movably

4
supported on said tubular supporting member for axial rotation relatively to the lever and provided on its surface with recesses adapted to register with said pins to permit of universal movement of the lever within its socket, said lever locking means capable of rotation axially of the lever to position a solid portion thereof to overlie the flat faces of said pins to preclude movement of the pins within the slots and the operative movement of the lever within its socket.

9. In combination with a tubular supporting member provided with a spherical socket, a lever member provided with a spherical fulcrum portion removably seated within said spherical socket, said socket provided at opposite sides with a vertical slot, a pair of pins extending laterally from said spherical fulcrum portion and projecting one into each of said slots and capable of movement therein on the operation of the lever, means mounted to rotate axially of the lever and supported by said supporting member and capable of movement to preclude movement of said pins within said slots and lock said lever from movement, a retaining member detachably secured to the supporting member for retaining the rotatable means in position on said support, said rotatable means when in a position to lock said lever from movement preventing the

detachment of said retaining means from said support.

10. In combination with a tubular supporting member provided with a spherical socket, a lever member provided with a spherical fulcrum portion removably seated within said spherical socket, said socket provided at opposite sides with a vertical slot, a pair of pins extending laterally from said spherical fulcrum portion and projecting one into each of said slots and capable of movement therein on the operation of the lever, a ring surrounding said lever and mounted to rotate axially thereof to preclude movement of said pins within said slots and lock said lever from movement, a retaining member positioned on said support for retaining the said ring in position thereon, means for detachably securing said retaining member to said supporting member, and means carried by said ring and overlying said securing means when said ring is rotated to lever locking position for preventing the detachment of said securing member from said support.

In testimony whereof I have signed my name to this specification in the presence of a subscribing witness.

GEORGE C. JENSEN.
